UNITED STATES PATENT OFFICE.

GEORGE THOMAS WYATT, OF OLIMSTEAD, KENTUCKY.

FURNACE.

Application filed December 30, 1921. Serial No. 526,003.

To all whom it may concern:

Be it known that I, GEORGE THOMAS WYATT, a citizen of the United States, and resident of Olmstead, in the county of Logan 5 and State of Kentucky, have invented a new and Improved Furnace, of which the following is a full, clear, and exact description.

My invention relates to a furnace, and 10 aims to provide certain new and useful improvements in connection with a device of this character and particularly over the construction shown in my prior Patent #732,610, issued June 30, 1903.

15 My present invention aims to provide a construction of the type stated by means of which any tendency of the parts becoming distorted or sagging incident to weight placed upon the same, and the action of heat, 20 will be counteracted so that the usefulness of the furnace will not be destroyed after a comparatively short period of use.

A further object of this invention is the 25 construction of a device of the character stated embodying the result set forth in the preceding paragraph, which furnace may be constructed at a nominal figure, and

Still further objects of this invention will 30 become apparent from the annexed specification taken in connection with the drawings, which latter illustrate one practical embodiment of the same and in which;

Figure 1 is a sectional view of the furnace embodying my improved furnace and 35 taken along the line 1—1 and in the direction of the arrows indicated in Figure 2.

Figure 2 is a transverse sectional view taken along the line 2—2 and in the direction of the arrows illustrated in Figure 1.

40 Figure 3 is an enlarged sectional view taken along the line 3—3 and in the direction of the arrows indicated in Figure 4, and

Figure 4 is a transverse sectional view 45 taken along the line 4—4 and in the direction of the arrows indicated in Figure 3.

As in the structure presented in my previous patent, my present invention provides a furnace which includes a table or 50 roof 5 from the side edges of which walls 6 extend downwardly, the stack 7 being also provided for the passage of the products of combustion. Also as in my previous patent, the device may be movably supported by providing suitable wheels 8 adjacent the forward end of the same and handles 9 adjacent

the rear ends of the same whereby an operator may readily move the furnace to any location desired.

Further I provide U-shaped supports 10 as 60 in my previous patent, but it will be noted that I preferably construct these elements of angle iron, to provide greater strength. Also the legs of the supports 10 are preferably riveted to the central beam-portions of 65 the supports as at 11 to make a rigid connection.

To further strengthen the furnace at this point, it will be noted that I utilize a bridge member which, as has been indicated in 70 Figure 4, is U shaped in cross section, the same including the body 12 formed with side walls 13, these latter portions being spaced from each other to an extent permitting of their straddling the body of a support 11 75 and acting as a bridge extending between the legs of the same. Also as has been clearly indicated in Figure 2 it will be noted that the walls 13 increase in height to a point substantially intermediate the ends of 80 the body 12 it being understood that due to this construction the resistance strength of the bridge member is greatly increased.

Thus all of the objects set forth in the preamble of this specification are accomplished, 85 and it will be appreciated that the use of the bridge member will not materially increase the cost of construction although the same will strengthen the parts of the furnace to a point at which no further objection 90 in this connection will be noted. It will be further understood that no objection will arise in connection with the use of my present improved construction incident to the difference in the ratio of expansion of the 95 bridge member with respect to the supporting member for the reason that these elements are merely placed in engagement with each other and not riveted together. In other words the supporting member 10 is 100 usually constructed of steel or wrought iron to provide the maximum amount of strength while the bridge member is preferably a casting to incorporate the maximum amount of heat resistance, and the ratio of expansion of 105 these two elements would naturally be unequal, and if they were affixed with respect to each other a distortion would invariably result. However as aforesaid, due to the mode of supporting the bridge member by 110 the supporting element, no objection on this score will be noted.

Obviously numerous modifications of structure might readily be resorted to without in the least departing from the scope of my claim; which is—

- 5 A furnace including in combination a table portion, U shaped supporting members for said table portion, and a bridging mem-

ber associated with each of said supporting members, said supporting and bridging members being all formed of metal but said 10 bridging members only being formed of cast iron.

GEORGE THOMAS WYATT.
